ATTORNEYS.

UNITED STATES PATENT OFFICE.

WILLIAM L. MERSFELDER, OF CINCINNATI, OHIO.

STOVE DOOR.

Application filed April 5, 1923. Serial No. 630,158.

To all whom it may concern:

Be it known that I, WILLIAM L. MERSFELDER, a citizen of the United States, and a resident of Cincinnati, in the county of Hamilton and State of Ohio, have invented certain new and useful Improvements in Stove Doors, of which the following is a full, clear, and exact description, reference being had to the accompanying drawing, 10 forming part of this specification.

My invention relates to doors for stoves, and more particularly to oven doors, and has as its general object the improvement mechanically and from the point of view of 15 external appearance of such doors.

The oven door of the present day is mounted on trunnions or projecting lugs, on the stove body, and on the door itself. The hinges so formed must be accurately formed, 20 and carefully joined by means of hinge pins or the like, and the hinges or journal box devices project from the outer face of the stove, making an unsightly appearance, and collecting dirt. The lack of a smooth front 25 makes it difficult to keep the stove entirely clean, and the fact that the oven door cannot be readily removed, leaves it as an impediment to a full clearing out of the oven.

It is my object to provide a door without 30 protruding hinges, in which the construction is simple and very economical, with no journal boxes, bolts or assembly cost. The door can be nickel plated throughout. Another object is to provide a door so counterweighted that it will close and open automatically 35 once it is started, and in which the opening movement is so controlled that the door cannot drop down with a sudden jar, but on the contrary will not have any slamming 40 action. In my new door there is no catch necessary to hold it closed, and the hinge device is arranged so as to bring the door panel flush with the base of the oven when the door is open, forming a projection in the 45 same plane as the oven bottom over which to slide dishes and pans without lifting.

These objects and advantages and other improvements to be noted I accomplish by 50 that certain construction and arrangement of parts to be hereinafter more specifically pointed out and claimed.

In the drawings:

Figure 1 is a perspective view of the door mounted in the oven frame of a stove.

Figure 2 is a section taken vertically

through center of the door when closed showing the hinge in side elevation.

Figure 3 is a detail elevation showing the hinge in side elevation on a larger scale, taken through the hinge pivot.

Figure 4 is a perspective of the retaining clip for one of the hinge structures.

Figure 5 is a side elevation showing this clip in place.

Figure 6 is a detail perspective of the clip and counterweight retaining segments.

Referring to the structure shown in the drawings which is merely an illustrative showing, by means of which I will endeavor to bring out the points of my invention, I 70 show an oven frame 1, and a door having a frame 2 and a panel 3.

The frame has elevated lugs 4, 4, which are cored in from the sides so as to permit screwing the panel to the door frame, without 75 tapping the door itself, or exposing any screw or bolt heads at the outside of the door.

At each lower corner of the door frame, there is provided an arm marked generally, 80 at 5, (see Figure 5), which arms have a special conformation so as to engage in slots 6, 6, in the oven frame, and rock to and fro over the curved bases 7 of these slots.

The arms have the curved under edges 8, 85 to ride on the curved slot bases 7, and the upper edges at 9 are also curved so as to bear on the top edges of the slots throughout the rocking movement. The arms project in a slight downward slant (considering the door 90 as closed), as indicated at 10, and this portion 10 terminates in a rounded shoulder 11, and an angle projection 12, serving the function of a hook. From the shoulder and hook the arms project as at 13, in the same 95 direction as the portions 10, with the top edges of the portions 13 formed as a seat for the counterweight and the retaining clip.

I employ the retaining clip instead of 100 two counterweights, as but one weight is necessary, and also, since the weight takes up some oven space, which should not be occupied at both sides of the oven.

Referring first to the clip, it is formed 105 with a body portion 14, which lies on the seat at the top edge of one of the arm portions 13. This body portion then bends downwardly as at 15, where it is slotted to sufficient size to slip over the end 13 of the 110

arm on which it is mounted. The slot terminates in an angular inner wall 15^a that engages the angular projection 12, when the body of the clip lies on the top of the portion 13, and the clip itself projects beyond the slot to a bearing edge 16.

Formed in the oven frame are a pair of segments 2^a extending inwardly along the sides of each slot 6. The edges 16 of the 10 clip bear on two of these segments. The result of this bearing, over which the clip rides as the door is moved, is that the door cannot be pulled off from its seat in the slots 6, and can only be removed by setting it 15 midway of open and closed position and lifting upwardly on the entire structure, to release the bearing of the clip. The clip can then be removed and the door removed from the oven frame. To hold the clip in place 20 a wire tie or cotter pin as indicated at 16^a, will preferably be used, a bolt or other fastening can also be used.

The counterweight is no different in construction from the clip, and its portions are 25 marked in a like manner. The portion 14, however, is extended and bent downwardly and formed into a weight portion 17, heavy enough to properly counterbalance the door.

The lower edge of the door frame, as 30 shown at 20, extends below the lower edge of the arms 5, 5, and is so set as to lie against the oven frame wall when the door is closed. As the door is swung open this edge 20 moves through the small arc permitting 35 the entire door to swing on the point 20 as a center, the curves at 7, 8 and 9 being formed on center at A.

The panel of the door is so set that this swinging on its pivots of the door will bring 40 it to the level of the bottom of the oven, said bottom being indicated by the lines 21 (Fig. 2), when the door is open.

The action of the counterweight, which 45 passes down below the oven bottom in a space left for that purpose, is such that when the door is swung open to some desired angularity to the perpendicular, it will then have shifted its center of gravity sufficiently with relation to the center of the weight, to 50 permit the door to fall entirely open. When the door is closed to the same position, the weight then has moved its center of gravity out far enough from the pivot center of the door to close it, and hold it closed without 55 latches or springs. The segments are formed on a curve which will cause the weight mounting clip to drag in its contact thereon, when the door nears its open position, and this acts to retard the door 60 motion to the end of avoiding a slamming action.

The weight clip needs no cotter pin or 65 wire to hold it in place, as the effect of gravity is sufficient to enforce a close following on the peripheries of the segments.

When the door is closed, a perfectly flat surface is presented, except for the thickness of the door where it laps the oven frame, with no protuberances to mar the appearance, catch the clothing and make cleaning 70 difficult. The door need not be attached when shipping the stove to the customer, and can be hung, and removed and rehung, whenever this is desirable.

It may be observed that the entire 75 structure is not only an improvement in function over the usual journaled door, but is much less expensive in construction, and assembly cost.

I have not attempted to describe alternative structure, in the above specification, but wish to cover the same, as coming within the scope of my invention, an example of which I have now described, and the inherent novelty of which I will now claim. 80

Having thus described my invention, what I claim as new and desire to secure by Letters Patent, is:—

1. In combination with the frame of a chamber to be opened and closed, said frame having slots therein, a door for closing said chamber having arms to project through said slots and rock therein, and a member on one of the arms, at least, removably secured thereto and presenting an 90 edge faced toward the chamber opening, and a curved projection on the oven frame over which said edge rides in the movement of the door.

2. In combination with a chamber having 100 a frame surrounding and opening therein, a door to close said opening, an arm and slot device, of the character described, and a securing device comprising a member adapted to hook over the arm and rest by gravity thereon, and a segmental projection from the chamber frame against which one of the free edges of said device rests during the complete movement of the door. 105

3. In a door mounting device of the nature described, a mounting arm having a curved portion upon which the door rocks, a downwardly extending hook portion and an upwardly directed seat portion, and a counterweight adapted to slip over the 110 arm and lie against said seat portion, and hook behind said hook portion.

4. In a door mounting device of the nature described, a mounting arm having a curved portion upon which the door rocks, a downwardly extending hook portion and an upwardly directed seat portion, and a counterweight adapted to slip over the 120 arm and lie against said seat portion, and hook behind said hook portion, and in combination with said arm and counterweight, a curved member shaped to form an abutment along which the hook engaging portion of the counterweight bears upon movement of the door. 125

5. In a door mounting device of the nature described, a mounting arm having a curved portion upon which the door rocks, a downwardly extending hook portion and an upwardly directed seat portion, and a counterweight adapted to slip over the arm and lie against said seat portion, and hook behind said hook portion, and in combination with said arm and counterweight, a curved member shaped to form an abutment along which the hook engaging portion of the counterweight bears upon movement of the door, said curved member arranged to form a friction brake on the counterweight portion during selected portions of the path thereof.
6. In combination with the frame of a chamber to be opened and closed, said frame having slots therein, a door for closing said chamber having arms to project through said slots, and rock therein, and means on one of the arms at least, removably secured thereto and presenting an edge faced toward the chamber opening, and a curved projection on the oven frame over which said edge rides in the movement of the door, said projection having its curve arranged to exert a braking friction against

the said edge at selected portions of its path.

7. A door hinge, comprising a vertically slotted member, a door having an arm projecting through the slot of said member, said slot having a curved lower wall, and the arm having a curved lower wall to engage the like wall of the slot, and means adapted to hook demountably on the arm to prevent its withdrawal from the slot, said means being formed to serve as a counterweight for the door.

8. A door hinge, comprising a vertically slotted member, a door having an arm projecting through the slot of said member, said slot having a curved lower wall, and the arm having a curved lower wall to engage the like wall of the slot, and means adapted to hook demountably on the arm to prevent its withdrawal from the slot, said means being formed to serve as a counterweight for the door, and a segmental projection at the side of said slot adapted to engage an edge of the said counterweight means to hold it in position during the movement of the arm.

WILLIAM L. MERSFELDER.
